[57] CLAIM

The ornamental design for a combined pocket tool case and key holder, as shown and described.

DESCRIPTION

FIG. 1 is a front elevational view of a combined pocket tool case and key holder showing my new design, the environmental structure shown in dotted lines being for illustrative purposes only and not a part of the design claimed;

FIG. 2 is a right side elevational view thereof;

FIG. 3 is a rear elevational view thereof;

FIG. 4 is a left side elevational view thereof;

FIG. 5 is a front elevational view thereof but opened up for selective removal of a key holder ring;

FIG. 6 is a bottom plan view thereof; and

FIG. 7 is a top plan view thereof.

FIG. 5.

FIG. 4.

FIG. 3.

FIG. 2.

FIG. 1.

FIG. 6.

FIG. 7.
